By Knight Bros

UNITED STATES PATENT OFFICE.

FREDRICK C. MILLER, OF NEWPORT, KENTUCKY.

DESIGN FOR A COUPLING-REACH FOR ROLLER-SKATES.

SPECIFICATION forming part of Design No. 16,129, dated June 16, 1885.

Application filed April 25, 1885. Term of patent 14 years.

To all whom it may concern:

Be it known that I, FREDRICK C. MILLER, a citizen of the United States, residing at Newport, in the county of Campbell and State of Kentucky, have invented and produced a new and original Design for a Coupling-Reach for Roller-Skates, of which the following is a specification, reference being had to the accompanying drawings, forming part thereof.

10 Figure I represents in side elevation my newly-designed coupling-reach for roller-skates, and Fig. II is a plan thereof. Fig. III is a transverse section on the line III-III, Figs. I and II.

15 The novel feature of this design consists in the peculiar shape or configuration of the reach shown in the drawings. The body of the reach is in the form of an arched or curved bar, 1, having a rounded under surface, 2. At 20 a distance above the extreme ends of the bar, and at the opposite ends, respectively, are upwardly-inclined bridge-pieces 3 and 4. 5 and 6 are depressions at the juncture of the bridge-pieces and the bar. At the ends of 25 the bridge-pieces are legs 7 and 8, and be-

neath the bridge-pieces are openings 9 and 10. Above the bridge-pieces are ribs 11 and 12. Over the leg 7 is a flat top, 13, having holes 14, and between the leg and top is a web, 15. The leg of the bridge-piece 4 has 30 an upwardly-curved top, 16, having holes 17 and 18, and between this leg and the top is a web, 19, having an opening, 20. 21 are holes in the bridge-pieces, and 22 are holes in the bar.

Having thus described my design, the following is what I claim as new therein and desire to secure by Letters Patent:

35 The design for a coupling-reach for roller-skates herein shown and described, the same 40 consisting of an arched or curved bar, having upwardly-inclined bridge-pieces at each end, downwardly-projecting legs at the ends of the bridge-pieces, a flat top surmounting one end, and an upwardly-inclined top surmounting the 45 other end.

FREDRICK C. MILLER.
